Norton Company, Worcester, Mass., a corpora-
tion of Massachusetts

Application August 21, 1942, Serial No. 455,674

4 Claims. (Cl. 121—45)

The invention relates to grinding machines, and more particularly to a hydraulically operated table reciprocating mechanism for a grinding machine.

One object of the invention is to provide a simple and thoroughly practical table reciprocating and reversing mechanism. Another object of the invention is to provide a table reciprocating mechanism in which a table actuated reversing valve serves to cut off the flow of fluid under pressure in one direction and in which the valve is positively shifted into a reverse position by fluid under pressure.

A further object of the invention is to provide a reversing mechanism with an improved reversing valve, comprising a two-part valve one of which slides relative to the other to facilitate reversal thereof by fluid under pressure. Other objects will be in part obvious or in part pointed out hereinafter.

The invention accordingly consists in the features of construction, combinations of elements, and arrangements of parts, as will be exemplified in the structure to be hereinafter described, and the scope of the application of which will be indicated in the following claims.

In the accompanying drawing, in which is shown one of various possible embodiments of the mechanical features of this invention,

Fig. 1 is a diagrammatic showing of the hydraulic control system of the improved table traversing and reversing mechanism;

Fig. 2 is a fragmentary vertical sectional view through the reversing lever and associated parts;

Fig. 3 is a sectional view of the reversing valve, showing the position of the valve parts when pressure is applied by starting the fluid pressure pump;

Fig. 4 is a similar vertical sectional view of the reversing valve, showing the valve parts in position after the reversing lever has initiated a reversing movement thereof;

Fig. 5 is a similar vertical sectional view, showing the reversing valve parts approaching a reverse position;

Fig. 6 is a similar vertical sectional view of the reversing valve showing the reversing valve and the auxiliary pilot valve in position during a normal reversal at the reverse end of the table stroke; and

Fig. 7 is a similar vertical sectional view with the main position of the reversing valve in a reverse position and with the fluid pump stopped.

As illustrated in the drawing, the machine embodying this invention comprises a base 10 which

supports a longitudinally reciprocable work supporting table 11 on the usual V-way and flat way (not shown) for a longitudinal reciprocatory movement relative to the base 10. A fluid operated reciprocating mechanism is provided to reciprocate the table 11, comprising a fluid pressure cylinder 12 which is fixedly supported by a pair of bracket end caps 13 and 14 fixedly mounted on the under side of the table 11. The cylinder 12 contains a pair of spaced pistons 15 and 16 which are connected by a pair of hollow piston rods 17 and 18, respectively, with a pair of hollow brackets 19 and 20, respectively, mounted on opposite ends of the base 10.

15 The base 10 is preferably formed as a box-like structure containing in its lower portion a reservoir 21 for the fluid pressure system. Fluid is drawn from the reservoir 21 through a pipe 22 by means of a motor driven fluid pressure pump

20 23. The pump 23 forces fluid under pressure through a pipe 24 to a table control or reversing valve 25. A variable pressure relief valve 26 is connected in the pipe line 24 to facilitate passing excess fluid under pressure within the system 25 directly through a pipe 27 into the reservoir 21 so as to maintain a substantially uniform operating pressure within the hydraulic system.

The control valve 25 is a piston type valve having two parts which slide relative to each other.

30 A slidably mounted valve stem 28 is provided with spaced valve pistons 29 and 30. A reduced cylindrical portion 31 of the valve stem 28 passes through a central aperture formed in a slidably mounted reversing valve member 32. The reversing valve member 32 is provided with spaced integrally formed pistons 33, 34 and 35. In the position of the valve parts as shown in Fig. 1, fluid under pressure passing from the pipe 24 enters a passage 36 in the valve casing and passes

35 through a port 37 into a valve chamber 38 located between the valve pistons 33 and 34 and passes out through a port 39 and a pipe 40 into a chamber 41 formed within the hollow bracket 19 and passes through the hollow piston rod 17 into a cylinder chamber 42 formed at the left-hand end of the cylinder 12.

40 In this position of the parts, fluid within a cylinder chamber 43 formed at the right-hand end of the cylinder 12 may pass through the hollow piston rod 18, through a chamber 44 formed within the bracket 20, and through a pipe 45, through a port 46, into a valve chamber 47 located between the valve pistons 34 and 35, and passes out through a port 48 and through a pipe

49 to a manually operable start and stop valve 51.

The stop and start valve 51 is preferably a combined stop-start and speed control valve and is preferably formed integral with the valve 25 but for the sake of simplicity of illustration, it has been illustrated diagrammatically in Fig. 1 as a separate valve unit. The valve 51 is preferably located in the exhaust side of the system so as to maintain a uniform fluid pressure on the operating side of the main cylinder 12 during the entire reciprocatory stroke of the cylinder 12 relative to the pistons 15 and 16. The valve 51 comprises a valve stem 55 having formed integrally therewith valve pistons 56 and 57. The control valve 51 is arranged so that it may be moved longitudinally from the full line position into a broken line position. The valve stem 55 is provided with an actuating knob 58 by means of which the valve may be rotarily adjusted. The right-hand end face of the valve piston 57 is formed as an angular plane face. By a rotary adjustment of the valve stem 55, the position of the angular end face of the piston 57 may be adjusted to open or close a V-port 59 to the desired and predetermined extent and serves as a fine adjustment to cut off more or less of the exhaust of fluid from the system, thereby precisely to regulate the reciprocatory speed of the table 11.

In order that the valve piston 57 may be maintained in the desired adjusted position during stopping and starting of the table, a serrated portion 60 is formed integral with the valve stem 55. A spring-pressed arrow-pointed plunger 61 is supported by the casing of the valve 51 and is maintained in engagement with the serrated portion 60 so that the valve stem 55 may be moved endwise or axially to stop and start the table movement without changing the speed adjustment thereof.

A manually operable start and stop lever 65 is pivotally supported by a stud 66 which is in turn supported by a projecting boss 67 formed integral with an apron 68 which is in turn fixedly supported on the front of the machine base 10. The control lever 65 is provided with a clearance aperture 69 which surrounds a sleeve 70. The sleeve 70 is rotatably supported on the valve stem 55 and is provided with a pair of diametrically opposed grooves 71 which are engaged by a pair of diametrically opposed studs 72 carried by the control lever 65. It will be readily apparent from the foregoing disclosure that when the control lever 65 is positioned as indicated in full lines (Fig. 1), the V-port 59 will be wholly or partially opened, allowing the table to move at the desired speed as governed by the rotary adjustment of the valve stem 55.

When it is desired to stop the reciprocatory movement of the table 11, the control lever 65 is shifted in a clockwise direction (Fig. 1) into broken line position 65a. This movement shifts the valve stem 55 together with the valve pistons 56 and 57 toward the right (Fig. 1) into the broken line position so that the valve piston 57 closes the V-port 59, thus cutting off the exhaust of fluid from the table cylinder 12 to stop the reciprocatory movement of the table 11.

When the throttle valve 51 is in a closed position, it is desirable to provide a suitable bypass whereby fluid may readily pass from the cylinder chamber 42 into the cylinder chamber 43 and vice versa to facilitate a manual traversing movement of the table 11. A pipe 80 is connected between the port 39 in the valve 25 and the valve 51. Similarly, a pipe 81 is connected between the port 48 in the valve 25 with the

valve 51. When the valve stem 55 is moved toward the right (Fig. 1) into a table stop position, a valve chamber 82 located between the valve pistons 56 and 57 moves into position 82a so that fluid may readily pass between the pipes 80 and 81 to facilitate a free passage of fluid between the cylinder chamber 42 and the cylinder chamber 43 of the table cylinder 12, so that the table may be readily moved longitudinally without the necessity of overcoming fluid under pressure within the system.

A manually operable table traverse mechanism may be utilized such as, for example, that shown in the prior United States Patent No. 2,071,677 and may comprise a manually operable hand wheel and a rack and gear mechanism for moving the work supporting table longitudinally. This mechanism is not considered to be a part of the present invention and consequently has not been illustrated or described in detail. For further details of the manually operable traversing mechanism, reference may be had to the United States patent above referred to.

A table actuated mechanism is provided for initiating a shifting movement of the reversing valve 25 comprising a reversing lever 85 which is supported on a rock shaft 86. The rock shaft 86 is journaled in a bearing 87 formed in the apron 68. A short downwardly extending lever 88 is fixedly mounted on the inner end of the rock shaft 86. The lever 88 is provided with a stud 89 which engages or rides in a vertically extending groove 90 formed in the valve stem 25. The reversing lever 85 is provided with a rearwardly extending stud 91 which is arranged in the path of a pair of adjustably mounted table dogs 92 and 93. The table dogs 92 and 93 are adjustably supported in a T-slot 94 formed in the front face of the work supporting table 11.

The valve 25 is provided with a valve chamber 100, located between the valve piston 29 and the valve piston 33, which serves to facilitate a shifting movement of the reversing valve 25 in a manner to be hereinafter described. It should be noted that the differential effective areas of the pistons 29 and 33 serve to aid in the reversal of the valve 25. A port 101, in the position of the valve 25 as shown in Fig. 3, connects the valve chamber 100 with a reservoir 102 formed in the valve casing. A port 103 connects fluid under pressure in the valve passage 36 with the valve chamber 100 during the shifting movement thereof.

Similarly, a valve chamber 105 is provided at the other end of the valve 25. The valve chamber 105 is formed between the valve pistons 30 and 35, respectively. It should be noted that a differential effective area is provided between the valve pistons 30 and 35 to facilitate the shifting of the valve parts during reversal of the valve 25. The valve chamber 105, in the position shown in Fig. 3, is connected by a port 106 with a port 107 and also connects with the valve passage 36. It should be noted that there is a differential piston area between the valve pistons 35 and 30 so that in the position of the valve as shown in Fig. 3, fluid under pressure passing through the pressure pipe 24 into the valve passage 36 will pass through the port 107 into the valve chamber 105 and, due to the differential effective areas of the pistons 35 and 30, the pressure will shift the valve member 32 toward the left into its extreme left-hand end position and also shift the valve piston 30 toward the right into the position illustrated in Fig. 3. A port 108 is provided which

serves during the shifting of the valve part toward the right to pass fluid from the valve chamber 105 into a reservoir 109 formed at the right-hand end of the valve 25.

In order to attain the main object of the invention, the end valve chambers 100 and 105 are provided to supplement the two-part slidable valve so that when the reversing lever is shifted by engagement with one or the other of the table dogs 92 or 93, the table movement will serve to shift the valve parts to cut off the exhaust of fluid from one side of the table cylinder 12, after which fluid under pressure operating through the end chambers 100 and 105 will automatically and positively shift the valve parts into a reverse position by fluid under pressure.

When the machine is idle, that is, when the fluid pressure pump 23 is shut off, the reversing lever 85 assumes either the full line position 85 or the broken line position 85c as shown in Fig. 1. During the time when the pump 23 is in operation, the lever 85 never assumes positions 85 or 85c but is positioned in broken line positions indicated in Fig. 1 as 85a or 85b. When the pump 23 is started to force fluid under pressure through the pipe 24 into the valve passage 36, fluid passes through the port 107 into the valve chamber 105 and shifts the valve part 32 into the extreme left-hand end position, after which the fluid pressure acting upon the valve piston 30 shifts the valve stem 28 toward the right into the position indicated in Fig. 3, which movement serves to throw the reversing lever 85 into position 85a (Fig. 1). Similarly, at the other end of the table stroke, due to the fluid pressure being admitted to the valve chamber 100, the valve parts assume the positions indicated in Fig. 7 with the reversing lever in position 85b.

The operation of the improved table traversing mechanism will be readily apparent from the foregoing disclosure. Assuming the pump 23 to be started, the fluid under pressure as above described enters the valve chamber 105 to shift the valve parts into the positions indicated in Fig. 3 and to shift the reversing lever into position 85a. Assuming the table 11 to be traveling toward the left, as indicated by the arrow in Fig. 1, this movement continues until the table dog 93 engages the stud 91 on the reversing lever 85 to rock it in a counterclockwise direction. This movement of the reversing lever 85 shifts the valve stem toward the right (Figs. 1, 3 and 4). Due to the position of the valve parts, the valve pistons 29 and 30 together with the slidably mounted reversing valve member 32 move toward the right under the influence of the moving table 11 until the valve piston 34 closes the port 48 to stop the exhaust of fluid from the cylinder chamber 43. The valve in this position is illustrated in Fig. 4. During this shifting movement of the reversing valve, fluid within the valve chamber 105 may exhaust through the port 108 into the reservoir 109 so that it does not retard materially the shifting movement of the valve parts.

During the shifting movement, the valve parts including the slidably mounted reversing valve member 32 move a sufficient distance toward the right so that the valve piston 33 uncovers the port 103, after which fluid under pressure from the pipe 24 entering the valve passage 36 enters the valve chamber 100. Due to the fact that the valve stem 28 is held by the reversing lever against shifting toward the left, fluid under pressure entering the valve chamber 100 acting upon the valve piston 33 positively and rapidly shifts the

reversing valve member 32 into its reverse position so that the valve parts assume the position illustrated in Fig. 5. In the position illustrated in Fig. 5, fluid under pressure entering the valve passage 36 passes into the valve chamber 47 located between the valve pistons 34 and 35 and passes out through the port 46 and the pipe 45 into the passage 44, through the hollow piston rod 18, into the cylinder chamber 43 to move the cylinder 12 and the table 11 toward the right. During the movement of the table toward the right, fluid within the cylinder chamber 42 is exhausted through the hollow piston rod 17, to the chamber 41, through the pipe 40, through the port 39, into the valve chamber 38, and passes out through the pipe 49, through the V-port in the speed control valve 51, and exhausts through the pipe 54 into the reservoir 21. The valve 51 serves to control the rate of exhaust of fluid and thereby to control and regulate the speed of movement of the table 11.

The table continues its movement toward the right until the reversing dog 92 engages the stud 91, after which continued movement of the table 11 toward the right shifts the reversing lever in a clockwise direction from position 85b toward position 85a. When the slidably mounted reversing valve member 32 reaches its extreme right-hand end position, as indicated in Fig. 7, the continued influence of fluid under pressure within the valve chamber 100 shifts the valve piston 29 and its associated parts toward the left into the position illustrated in Fig. 7. During the initial shifting movement of the lever 85 from position 85b in a clockwise direction, the valve stem 28 is shifted toward the left together with the slidably mounted reversing valve member 32. The initial movement of the valve parts is under the influence of the table 11 as transmitted through the reversing lever 85. This movement of the valve parts is continued until the valve piston 34 shifts toward the left from the position illustrated in Fig. 7 to close the exhaust port 48, thus stopping the exhaust of fluid from the cylinder chamber 42. When the valve parts reach this position, the port 101 is opened so that fluid within the valve chamber 100 may pass into the reservoir 102. The valve parts have also moved sufficiently toward the left so that the valve piston 35 has uncovered the port 106, thus admitting fluid under pressure into the valve chamber 105. The admission of fluid into the chamber 105 acting upon the valve piston 35 serves to rapidly and positively shift the slidably mounted reversing valve member 32 toward the left under the influence of fluid under pressure into its extreme left-hand end position, as illustrated in Fig. 3, in which position the fluid flow is reversed and fluid under pressure conveyed in a manner hereinabove described to the cylinder chamber 42 to cause the table 11 to start its movement toward the left. Fluid under pressure entering the valve chamber 105 then shifts the valve piston 30 toward the right so that the valve parts again assume the positions illustrated in Fig. 3.

If it is desired to stop the reciprocatory movement of the table 11, the control lever 65 may be shifted in a clockwise direction into position 65a. This movement serves to shift the valve piston 57 to close the V-port 59, thus cutting off exhaust of fluid from the table cylinder 12 to stop the table movement. When the valve 51 is in a stop position, the pipe 80 is directly connected with the pipe 81 through a valve chamber 82 which is then positioned in position 82a shown in broken

lines in Fig. 1, so that fluid may readily by-pass between the cylinder chamber 42 and the cylinder chamber 43 to facilitate a manual traversing movement of the table 11.

It will thus be seen that there has been provided by this invention apparatus in which the various objects hereinabove set forth together with many thoroughly practical advantages are successfully achieved. As many possible embodiments may be made of the above invention and as many changes might be made in the embodiment above set forth, it is to be understood that all matter hereinbefore set forth or shown in the accompanying drawing is to be interpreted as illustrative and not in a limiting sense.

I claim:

1. In a hydraulically operated table reciprocating mechanism including a piston and cylinder, a source of fluid under pressure, a piston type reversing valve comprising a casing, a slidably mounted valve member therein having a pair of spaced valve pistons thereon, a reversing valve slidably supported on said member having a plurality of spaced integrally formed pistons, the movement of said reversing valve in either direction being limited by said casing, the effective areas of the reversing valve pistons being greater than the effective areas of the spaced valve pistons on said valve member, a valve chamber formed at each end of the reversing valve between the reversing valve and said spaced valve pistons, respectively, table actuated means to shift said valve member and said reversing valve to shift the reversing valve to a central position, and a valve port for each of said chambers successively connecting a source of fluid under pressure with said valve chambers, one of said ports being opened during reversal at each end of the table stroke to admit fluid under pressure directly from said source to one of said chambers positively and rapidly to shift the reversing valve so as to reverse the flow of fluid under pressure to said cylinder after which, due to the effective area of the reversing valve piston, fluid under pressure in the end chamber will shift both the reversing valve and the slidably mounted valve member into the extreme reverse position.

2. In a hydraulically operated table reciprocating mechanism including a piston and cylinder, a source of fluid under pressure, a piston type reversing valve comprising a slidably mounted valve member having a pair of spaced valve pistons thereon, a reversing valve slidably supported on said member having a plurality of spaced integrally formed pistons, the effective areas of the reversing valve pistons being greater than the effective areas of the spaced valve pistons on said valve member, a valve chamber formed at each end of the reversing valve between the reversing valve and said spaced valve pistons, respectively, table actuated means to shift said valve member and said reversing valve to shift the reversing valve to a central position, and a valve port for each of said chambers successively connecting a source of fluid under pressure with said valve

chambers, one of said ports being opened during reversal at each end of the table stroke to admit fluid under pressure directly from said source to one of said chambers positively and rapidly to shift said reversing valve independently of said valve member into a reverse position.

3. In a hydraulically operated table traversing mechanism including a piston and cylinder, a source of fluid under pressure, a reversing valve therefor including a valve casing, a valve member having a pair of spaced valve pistons slidably mounted within said casing, a reversing valve member slidably supported in said casing and slidably relative to said valve member and having a plurality of spaced integrally formed valve pistons thereon, the effective areas of the reversing valve pistons being greater than the effective areas of the spaced valve pistons on said valve member, a valve chamber formed at each end of the reversing valve between the reversing valve and said spaced valve pistons on said valve member, respectively, a reversing lever and adjustable table dogs to shift said valve member and said reversing valve to shift the reversing valve to a central position, and a port opened during said movement to admit fluid under pressure directly from the source to one of said chambers positively and rapidly to shift the reversing valve independently of said valve member into a reverse position so as to reverse the movement of said table.

4. In a hydraulically operated table reciprocating mechanism including a piston and cylinder, a source of fluid under pressure, a piston type reversing valve comprising a casing and a slidably mounted reversing valve member having a plurality of integrally formed pistons thereon which are arranged to reverse the flow of fluid under pressure to a table cylinder, the movement of the reversing valve member in either direction being limited by said casing, a slidably mounted valve member having a portion slidable within the reversing valve member, spaced valve pistons on said second valve member which are spaced from the opposite ends of the reversing valve member to provide lost motion between the two valve members, valve chambers formed between said latter pistons and the ends of said reversing valve member, a table actuated reversing lever operatively connected to actuate said second valve member which in turn moves the reversing valve member to cut off the flow of fluid under pressure to the table cylinder, and means to admit fluid under pressure directly from said source to one of said valve chambers during reversal rapidly and independently to shift the reversing valve member so as to reverse the flow of fluid under pressure to said cylinder after which, due to the effective area of the reversing valve piston, fluid under pressure in the end chamber will shift both the reversing valve and the slidably mounted valve member into the extreme reverse position.
